(57) **CLAIM**

We claim the ornamental design for an airgun body, substantially as shown and described.

DESCRIPTION

FIG. 1 is a perspective view of an airgun body according to the present invention;

FIG. 2 is a right side elevation view of the airgun body of FIG. 1;

FIG. 3 is rear elevation view of the airgun body of FIG. 1; FIG. 4 is a front elevation view of the airgun body of FIG. 1;

FIG. 5 is bottom plan view of the airgun body of FIG. 1; and, FIG. 6 is a top plan view of the airgun body of FIG. 1.

The broken lines in the Drawings are for illustrative purposes only in order to show the environment in which the design is associated and form no part of the claimed design.

The left side elevation view is a mirror image of the right side elevation view, and has therefore not been shown separately in the Drawings.
